UNITED STATES PATENT OFFICE.

RICHARD KÜCH, OF HANAU, GERMANY, ASSIGNOR, BY MESNE ASSIGNMENTS, TO
GENERAL ELECTRIC COMPANY, A CORPORATION OF NEW YORK.

MEANS FOR STARTING ALTERNATE-CURRENT MERCURY-VAPOR LAMPS.

1,101,197.

Specification of Letters Patent.

Patented June 23, 1914.

Application filed May 23, 1910. Serial No. 562,975.

To all whom it may concern:

Be it known that I, RICHARD KÜCH, a subject of the German Emperor, and resident of Hanau o. M., Germany, have invented certain new and useful Improvements in Means for Starting Alternate-Current Mercury-Vapor Lamps, of which the following is a specification.

Mercury vapor rectifiers are known in which both cathodes and anodes are of mercury. In these the starting, by tilting the apparatus, presents no difficulties, as the anodes are close to the cathode so that, on tilting the apparatus, one of the anodes is brought immediately into temporary contact with the cathode and the arc can be struck without difficulty and without the use of an auxiliary anode as required with stationary anodes. In mercury vapor lamps however in which the cathode and anodes are of mercury, the case is different, as, owing to the nature of the lamps, the anodes must be arranged at a considerable distance from the cathode in consequence of a long illuminating tube being necessary for the production of the arc. If it be desired to start such lamps in the same way as the aforesaid rectifiers, that is without an auxiliary anode, it is necessary to cause the mercury to run from the anodes to the cathode or vice versa, to give the lamp a tilting motion which causes the mercury to run from the anodes, or from one of the anodes, to the cathode and back again therefrom this latter method being generally used as, for the proper working of the lamp, care must be taken that the mercury shall always be in the proper proportion at both the anodes and cathode. In this case, the difficulty is that the thin line of mercury which temporarily connects the anodes with the cathode, often causes a short circuit between the anodes when this connection is removed, so that the arc cannot be formed, or so that, after the formation of the arc, the thin line of mercury which returns to the anodes meets, at the same time, several interconnected anodes and the arc which has been started is extinguished. I have found that these failures to start the lamps can be prevented if, by suitable placement of the anode vessels, or by suitable arranged partitions, the thin line of mercury be constrained to distribute itself in such a manner that is impossible for a short circuit to occur between the an-

odes when the thin line of mercury is broken after the arc is formed. Three examples of such an arrangement are illustrated in the accompanying drawings and for the sake of simplicity it is presumed that there are only two anodes, that is that a single phase alternating current is used, to work the lamp.

In these drawings, A_1 and A_2 are the two anode vessels, K is the cathode vessel, and L is the illuminating tube. The said tube has, in the position of rest, a slight inclination toward the cathode and forms two branches at the anodes.

In Figure 1, the anode vessel A_2 lies lower than the anode vessel A_1 . If the lamp be attached to an axis, as shown in the figure, and this axis be turned in the direction of the arrow, the vessel A_2 is raised to such an extent that some mercury flows out of it to the cathode, while mercury cannot run out from the vessel A_1 . In this way short-circuiting between the mercury in the vessels A_1 and A_2 is avoided when the thin line of mercury is broken. On account of the unsymmetrical position of the anode vessels, on tilting the lamp back into its normal position, the mercury flows back again toward the vessel A_2 without short circuiting taking place between the mercury in the vessels A_1 and A_2 .

In Fig. 2 the anode vessels are symmetrically arranged with respect to the illuminating tube. In this case also, on tilting the lamp, mercury flows from the vessel A_2 only. The receding thin line of mercury returning simultaneously to both anode vessels would however conductively connect the two anodes and the arc formed would be extinguished. In order to avoid this, a partition W , is provided which causes the mercury to flow entirely to the vessel A_2 by closing the path toward the vessel A_1 .

In Fig. 3 the rotatable axis is so situated that, on tilting the lamp, the mercury runs simultaneously from both anode vessels. The long partition wall S , which extends along the length of the tube however divides the lower half of the illuminating tube so that the flow of mercury from the anodes takes place in two separate lines, and, when these jets are broken, no short-circuiting can occur between the anodes. The return of the mercury to the anodes likewise takes place in two lines separated from each other.

Although my invention has been described

with reference to a device using single phase alternating current and, therefore, having but two anodes, it will of course be understood that the invention is not limited 5 to apparatus of any particular number of phases.

I claim:

1. The combination with an alternating current mercury vapor device having a plurality of anode chambers and adapted to be tilted to cause mercury to flow to and from the anode chambers to start the device, of means for preventing the mercury from forming a short circuit between two anodes.
- 10 2. An alternating current mercury vapor lamp adapted to be tilted to cause the mercury to flow longitudinally of the illuminating tube to and from its anode end when it is being lighted and having two anode chambers, and a partition providing two separated passages connecting the tube with the anode chambers and positively preventing the mercury from forming a short circuit between the anodes.
- 15 3. An alternating current mercury vapor lamp adapted to be tilted to cause the mercury to flow longitudinally of the illuminating tube to and from its anode end when it is being lighted and having two anode chambers, and a partition extending longitudinally of the interior of the illuminating tube and providing two separated passages con-

nected the tube with the anode chambers, for the purpose described.

4. A vapor electric device comprising a liquid metal cathode, a plurality of anodes and means for guiding a stream of liquid metal from the cathode to one of the anodes and directing said stream away from the other anode.

40 5. An alternating current vapor electric lamp comprising a mercury cathode, a plurality of anodes located side by side opposite said cathode, and means for guiding a stream of mercury to one anode to the exclusion of the other anode to start the lamp.

45 6. A mercury vapor electric lamp, comprising an envelop, a mercury cathode at one end of said tube, and a plurality of anodes at the opposite end of said tube, and means for assisting a stream of mercury flowing lengthwise the envelop to contact with one anode prior to another anode whereby an arc may be started between the cathode and said anode before a short-circuit can occur 50 between anodes.

In testimony whereof I have signed my name to this specification in the presence of two subscribing witnesses.
